UNITED STATES PATENT OFFICE.

WINFRED W. HARRIS, OF WINTHROP, MASSACHUSETTS, ASSIGNOR TO JAMES S. WILSON,
OF CHELSEA, MASSACHUSETTS.

FLEXIBLE TUBE

No. 880,822.

Specification of Letters Patent.

Patented March 3, 1908.

Application filed June 7, 1905. Serial No. 264,117.

To all whom it may concern:

Be it known that I, WINFRED W. HARRIS, of Winthrop, in the county of Suffolk and State of Massachusetts, have invented certain new and useful Improvements in Flexible Tubes, of which the following is a specification.

This invention relates to a new and improved flexible tube or conduit for electric wires.

Figure 1 in front elevation shows a tube constructed in accordance with my invention, the different members of the tube being broken away to show the relative arrangement of the parts. Fig. 2 is a front elevation of the lining, part of the same being shown in section, to illustrate the spiral arrangement. Fig. 3 is a cross-sectional view of the tube.

Referring to the drawings, the form of tube therein shown is constructed and arranged like the tube shown in patent to Herrick, No. 456,271, although my invention is not to be understood as being limited to this particular form. In tubes of this general construction having a lining composed of a spirally arranged strip, it is possible by taking hold of the strip to pull the latter entirely out of the tube in cases where the material of the strip is stronger than the friction between the strip and its covering. This might be occasioned by the wire engaging the strip when being pulled through, or it might be done purposely to increase the diameter of the tube. In either event the efficiency of the tube is injured. By my invention this defect is overcome, since I so treat this lining after it is in position that any pull upon this lining, instead of drawing the lining out of the tube tears a piece off of the strip forming the lining at a weakened or scored place, thus preventing only a small piece from being pulled out at a time.

The strip of lining 1, the tape 4 and covering 5 may be of any preferred material, although ordinarily the strip 1, composing the inner lining, is made of fibrous material.

In practice the strip 1 is wound upon a suitable mandrel in a spiral manner in the form of a tube. Thereafter the tape 4 is applied in a spiral manner to break joints with the joints 2 of the lining strip 1. Thereafter the woven or otherwise fashioned covering 5 is applied.

3 represents a scored or weakened line formed in the strip 1, after or as the said strip is applied to the mandrel, the said scored or weakened line 3 running at an angle to the path of the joint 2. While this angle may be varied, the path of the scored line should be as nearly at right angles to the axis of the tube as practical. The depth of the scored line 3 or the degree to which the strip is weakened depends upon the material of which the tape is composed and the friction or adhesion between the strip 1 and the tape 4 or other covering, the purpose being to so score or weaken the strip 1 at the places 3, that any pull upon said strip, instead of pulling out the strip by the separation of the strip at the joints 2, will cause the strip to tear on the scored or weakened places 3, thus making it practically impossible to pull out more than a mere ring of the lining. While I have in the form shown weakened the lining by means of the scored line 3, I do not wish to be understood as limiting my invention to such a method to accomplish the desired result. In the form shown, the weakened line 3, passes spirally and progressively around the tube in a direction opposite to that of the joint 2.

Further, my invention is not to be understood as being restricted to a tube composed of the tape 4 and covering 5, but comprises a scored lining irrespective of the form or material of the covering or the material of the lining.

Having thus explained the nature of my invention and described a way of making and using the same, although without attempting to set forth all of the forms in which it may be made or all of the modes of its use, what I claim and desire to secure by Letters Patent is—

A conduit comprising a suitable covering, a lining arranged therein composed of a strip of material arranged in a spiral form, said lining being formed with a weakened portion arranged at an angle to the spiral path formed by the edges of the strip, whereby the path of one intersects the path of the other at predetermined points.

In testimony whereof I have affixed my signature, in presence of two witnesses.

WINFRED W. HARRIS
